UNITED STATES PATENT OFFICE.

HENRY W. LEWIS, OF INDIANAPOLIS, INDIANA.

STREET AND STATION INDICATOR.

1,127,461.

Specification of Letters Patent.

Patented Feb. 9, 1915.

Application filed January 27, 1914. Serial No. 814,773.

To all whom it may concern:

Be it known that I, HENRY W. LEWIS, a citizen of the United States, residing at Indianapolis, in the county of Marion and State of Indiana, have invented new and useful Improvements in Street and Station Indicators, of which the following is a specification.

This invention relates to a street and station indicator for railroad cars, the primary object thereof being to provide an indicator which is adapted to be actuated by track trip devices disposed in advance of street crossings or stations so as to indicate these stopping points upon approaching the same.

A further object of the invention is to provide a device of this character which successively indicates the street crossings or stations on the line in their proper order upon movement of the car in a reverse direction.

A still further object is the provision of a device of the class described which is of the simplest possible construction so as to render the same inexpensive to manufacture and capable of being installed readily and cheaply and which at the same time, will be durable and efficient in operation.

The invention consists in the features of construction, combination and arrangement of parts hereinafter fully described and claimed, reference being had to the accompanying drawings, in which:

Figure 1 is a longitudinal sectional view taken through a railroad track and car mounted thereon, showing the track trip device in inoperative position. Fig. 2 is a similar view showing the trip device in operative position as caused by engagement of a car wheel therewith when the car is traveling in one direction. Fig. 3 is a similar view showing the track trip device in operative engagement with the car-carried indicating mechanism when the car is moving in reverse direction. Fig. 4 is a transverse sectional view through the car-carried indicating mechanism, a portion thereof being broken away. Fig. 5 is a transverse sectional view on line 5—5 of Fig. 1. Fig. 6 is a detail perspective view of the actuating mechanism for the forward movement ratchet wheel of the indicator drum. Fig. 7 is a similar view of the actuating mechanism for the reverse movement ratchet wheel. Fig. 8 is a longitudinal, vertical sectional

view, taken through a portion of the car, showing the street indicator in fragmentary side elevation.

In the drawings, the numeral 1 indicates the body of a street railway car which has the street and station indicating mechanism 2 mounted therein. This mechanism includes a pair of drums 3 and 4 which are rotatably mounted in the bearing standards 5 and 6, and an endless indicating belt 7 constructed of woven fabric or other material which bears the names of the respective street crossings or stations and which is adapted to be operated step by step around the said drums by the means provided for the purpose, as the car advances along the track. One stretch of this belt is adapted to pass, during its passage from one drum to the other, over a roller 8 and around a second roller 9, both of which are journaled in suitable bearings 10 and 11, respectively, so that it will pass through an exhibiting casting 12 positioned in the front wall 13 of the car in rear of the motorman's compartment and which is provided with a view opening 14 through which the successively displayed names may be viewed by the passengers in the car. The axles 15 and 16 of the drums 3 and 4, respectively, are provided at adjacent ends thereof with pulleys 17 and 18 which are connected by a belt 19 which is intended to cause the drums to operate jointly in a positive manner.

The axle 16 of the drum 4 is provided at its end opposite to the end upon which the pulley 18 is mounted with a pair of ratchet wheels, which are indicated by the numerals 20 and 21, and whose teeth 22 and 23, respectively, are oppositely raking, the said ratchet wheels being fixedly secured to the axle. A transversely extending horizontal rock shaft 24 is journaled in suitable bearings 25 and has an arm 26 which extends outwardly in the plane of the ratchet wheel 20. A vertically movable dog 27, which is constructed preferably of resilient metal, has its lower end connected to the free end of the arm 26, as at 28, this end of the dog being in the form of a spring coil, which renders the engaging end 29 thereof radially yieldable with respect to the axle 16 and maintains the same normally in engagement with the teeth 22 of the ratchet wheel 20. A radially yieldable locking tongue 30 is attached at its lower end, as at 31, to the

frame of the car in close proximity to the dog 27 outwardly with respect thereto and has its engaging end 32 normally in engagement with the teeth of the ratchet wheel 20 5 immediately above the engaging extremity 29 of the dog. This locking tongue 30 is adapted normally to lock the said ratchet wheel against retrograde movement, whereas the dog 27 is adapted to impart movement to the said ratchet wheel in the direction of the arrow *a* upon corresponding movement of the rock shaft 24. A second arm 33 projects outwardly from the rock shaft 24 and has its free end connected by 10 means of a transverse pin 34 with the adjacent end of a vertically movable lever 35, the said pin being engaged within the longitudinal slot 36 in the said end of the lever 35. This lever is pivoted at 37 so that it is 15 movable in a plane parallel to the plane of the arm 33. The opposite end of the lever 35 is connected in similar manner, as at 38, with the upper end of a vertically slidable bar 39, to the lower end of which a shoe 40 is 20 secured, the said bar being movable within the guides 39^a. The construction of this shoe will be described more fully herein-after. The bar 39 is disposed so that the shoe 40 will be located immediately inward 25 with respect to the innermost wheels 41 of the adjacent car truck 42 and is located inward with respect to the right hand track rail 43, considering that the car is moving in the direction of the arrow *b* and in 30 slightly spaced relation to the same. A second horizontal rock shaft 44 is 35 journaled in the bearings 45 in parallel relation to the shaft 24 and consequently the axle 16 of the drum 4. An outwardly projecting arm 46 is provided upon the shaft 44 and has an operating dog 47 similar to the previously described dog 27 attached in like manner thereto so that its laterally yieldable engaging extremity 48 normally 40 engages the teeth 23 of the ratchet wheel 21. A locking tongue 49 identical in construction to the locking tongue 30 is attached to the car frame, as at 50, and has its laterally yieldable engaging end 51 normally in engagement with the teeth of the ratchet wheel 21 45 directly above the engaging extremity of the dog 47. This locking tongue serves to prevent retrograde movement of the axle 16 during operation of the ratchet wheel 21 in the direction of the arrow *c* by the action of the dog 47. An inwardly projecting arm 52 is provided upon the shaft 44 and has its free end connected by means 50 of a pin and slot connection such as is shown at 53, with the adjacent end of a lever 54, which latter is pivoted at 55 for movement in a vertical plane parallel to the plane of movement of the arm 52. A vertically slidable bar 56, which is mounted 55 within the guides 57, is connected at its up-

per end by means of a pin and slot connection 58, and a shoe 59 similar to the shoe 40 is provided upon its lower end and is normally positioned at the same level as the latter. The shoe 59 is also disposed inwardly with respect to the adjacent truck wheel 41 and immediately in advance of the shoe 40. 70

Two angular tripping members 60 and 61 are pivotally mounted upon the axle 16. 75 The member 60 is provided upon its arm 62 which extends forwardly from the axle 16 with an axial extension 63 for engagement with the inner face of the dog 47, whereby said dog will be forced outwardly 80 and will move the locking tongue 49 similarly out of engagement with the teeth 23 of the ratchet wheel 21, upon movement of the tripping member 60 in the direction of the arrow *c*. The opposite arm 64 of the 85 said tripping member, which projects rearwardly and downwardly from the axle 16 is provided with a longitudinal slot 65 for the reception of a transverse pin 66 provided in the adjacent end of a forwardly 90 projecting arm 67 formed on the rock shaft 24. The tripping member 61 has an axial extension 68 provided upon its rearwardly projecting arm 69 for engagement with the dog 27, whereby the said dog and the locking tongue 30 will be moved into inoperative 95 position in like manner upon movement of the tripping member 61 in the direction of the arrow *a*. The opposite arm 70 of the last named tripping member is connected 100 with the free end of an upwardly and rearwardly projecting arm 71 provided upon the rock shaft 44 by means of a pin and slot connection 72.

The shoe 40 is pivotally connected to the 105 lower end of the bar 39 by means of the transverse pintle 73 and is provided with a limiting extension 74 projecting upwardly therefrom for engagement with the front face of the said bar, so that the said shoe 110 will turn on its pivot when its rear face 75 becomes engaged with a track obstruction, but which will assume a rigid position with respect to the bar 39 so as to cause upward movement thereof upon engagement of a 115 track obstruction with the opposite beveled face 76 of the shoe, during movement of the car in the direction indicated by the arrow *b*. The shoe 59 is constructed identically 120 the same as the shoe 40 but is disposed so 125 that its beveled face 77 is opposite to the face 76 of the shoe 40 and is thus adapted to cause upward movement of the bar 56 upon becoming engaged by a track obstruction, during movement of the car in the direction 125 of the arrow *b*.

At a considerable distance in advance of each street crossing or station, preferably a few yards past the preceding street or station, as the case may be, a track trip de- 130

vice is positioned. Each of these devices consists of a rocking member or lever 78 which is pivotally suspended beneath the right-hand track rail 43 by means of the 5 pivoted member 79, a vertically movable engaging member 80 being provided upon the extremity of the longer arm 81 of the said lever, whose upper end is rounded, as at 82, for engagement with the shoes carried by 10 the indicator mechanism of each car, and a vertically movable member 83 is provided upon the opposite shorter arm of the lever 78. The head 84 provided upon the upper end of the member 83 is disposed normally 15 flush with the tread surface of the rail against the inner face thereof so that the flanges of the car wheels mounted upon the said rail will engage the same to cause depression thereof and thus throw the member 80 into its uppermost operative position. 20 The end faces of the head 84 of the member 83 are beveled upwardly, as at 85, so as to cause the wheel flanges to ride onto the same without excessive shock or horizontal strain 25 upon the said member. The member 78 is constructed slightly greater in length than a car truck and is disposed with its head 84 in advance of the engaging member 80 in order that all the wheels of each truck 30 will pass over the engaging member before the leading wheel of the truck rides onto the head 84. It should thus be evident that the engaging member cannot become caught in the low hanging portions of a car truck so 35 as to cause damage to either. The engaging member 80 is adapted to be projected upwardly into the path of the beveled face 77 of the shoe 59 when one of the foremost wheels of the advance truck 42 passes onto 40 the head 84. The said head is constructed of such horizontal length that the said wheel will not leave the same until the other shoe 40 has passed over the engaging shoe 80. 45 When a car equipped with the mechanism described above, advances along one track in a single track system, the track trip devices located in advance of the successive street crossings or stations will simply tilt 50 the rearmost shoe 40 carried by the car, without actuating the corresponding face 77 of the foremost shoe 59 so as to cause upward movement of the operating bar 56. This movement of the bar 56 will cause the 55 lever 54 to rock upon its pivot and thus impart opposite motion to the rock shaft 44, whereupon the dog 47 will engage one of the teeth 23 of the ratchet wheel so as to rotate the ratchet wheel and consequently the shaft 60 16 in the direction of the arrow *c*, it being understood that the shoe 59 is normally in its lowermost position in order that the dog 47 will be in its lowermost position also. This movement of the axle 16 will cause the 65 indicating sheet to move one step as the said shoe rides over the engaging member of the track trip device. The name of the next succeeding stopping point is thus exhibited through the view opening 14 of the casing 12. In this manner, names of the successive streets will be indicated for the passengers as the car advances along the track in this direction. 75 In the event that the car should move backward for any reason so as to move over the track trip device in advance of one of the stations, the engaging member 80 of the trip device will become engaged operatively with the beveled face 76 of the shoe 40 so as to cause reverse operation of the axle 16 and the attached winding drum in a manner which should be readily understood. This movement will cause the street indicating plate to move in the reverse direction so as to indicate the street previously passed, a second time. It is evident that this street will be indicated just before the car approaches it so that the passengers will be given short warning, but this movement of the car would be an unusual occurrence. In case the railroad is a single track system and the cars move in both directions upon the track without being reversed end for end prior to each trip, it would become necessary to locate the track trip devices 90 midway between stations or streets in order that proper warning should be given to passengers upon a car moving in either direction when a car is approaching a stopping point. 95 100 In single track systems, it often proves desirable to reverse the position of each car after it has made a trip in one direction and before it makes the return trip. In order that the indicating mechanism will operate properly in such a case, a pair of auxiliary shoes 86 and 87, similar in construction to the previously described shoes 40 and 59, are secured to the lower ends of the vertically slidable operating bars 88 and 89, respectively, mounted within the guides 90 and 91 provided adjacent to the opposite side of each car. These shoes 86 and 87 are disposed so that the beveled active faces 92 and 93 thereof face oppositely with respect 105 to the beveled faces of the main shoes 59 and 40 respectively. The upper end of the operating bar 58 is pivotally connected, as at 94, to the adjacent end of a vertically movable lever 95 which latter is pivoted upon the transverse pin 96 for movement in a plane parallel to an operating arm 97 secured fixedly to the rock shaft 44, the meeting ends of the lever 95 and arm 97 being connected pivotally, as at 98. The upper end of the operating bar 89, however, is pivotally connected, as at 99, to the adjacent end of a vertically movable lever 100, the latter being mounted upon a transverse pivot pin 101. The opposite end of the said 110 115 120 125 130

lever, 102, is connected pivotally to the adjacent end of a vertically movable arm 103 which is attached movably to the rock shaft 24. Therefore, when a car is reversed end 5 for end and returns along the single track in the direction of the arrow *d*, the active face 92 of the auxiliary shoe 86 will become engaged by the engaging member of the respective track trip devices so as to cause operation 10 of the rock shaft 44, which latter may be termed the "forward movement" shaft. The indicating mechanism will thus be operated in its reverse order. The shoe 87 will ride over the engaging members of 15 the track trip devices unless the car should happen to move backward to a sufficient distance, whereupon the active face 93 of the shoe will engage the engaging member of any one of the trip devices so as to cause 20 operation of the "reverse movement" rock shaft 24.

In a double track system, the track trip devices will be disposed adjacent to corresponding rails on both tracks, it being found 25 preferable to position the said devices near the outermost rail in each instance. In a belt line, wherein one end of each car only is the forward end, the main shoes 59 and 40 will be the only ones used in operating 30 the indicating mechanism.

Extra shoes 104 are pivotally attached to the depending portions 106 of the rigid arms 107 which project inwardly from the operating members 39 and 56, respectively. 35 These shoes 104 have their active beveled faces 109 disposed oppositely with respect to the beveled faces 76 and 77 of the main shoes 40 and 59, and are adapted to be used in connection with the trip devices employed 40 in connection with a countertrack.

From the foregoing description, taken in connection with the accompanying drawings, it should be apparent that I have provided a street and station indicator which 45 is adapted to be used upon electric cars or a steam train for indicating in proper succession the different stopping points as the train approaches the same, and which will operate accurately under all the varied conditions of traffic which may present themselves in practice. I desire to have it understood, however, that minor changes in the construction of the device which are 50 found necessary in practice may be resorted to without departing from the scope of the invention.

Having thus described my invention, what I claim is:

1. In a device of the class described, the 60 combination of a train-carried indicating apparatus including a rotatably mounted axle, a name-bearing element connected with the axle, a ratchet wheel mounted fixedly upon the axle, a rock shaft journaled par- 65 allel to the said axle, a lateral arm provided

upon said rock shaft, a dog mounted upon said arm and having a laterally yieldable free extremity normally engaged with the teeth of the said ratchet wheel for operating the latter in one direction upon movement of the rock shaft, a second ratchet wheel connected fixedly with the axle, a second rock shaft journaled parallel to the said axle, a radial arm provided upon the last-named rock shaft, a second dog attached to 70 the said arm and having a radially yieldable free extremity for engagement with the second ratchet wheel to cause movement of the axle in a direction opposite to that in which it is moved by the first-named dog, 75 means for moving each dog outwardly into inoperative position upon operative movement of the other dog, an operating device connected with the first rock shaft and adapted to oscillate the same upon being 80 actuated, and a second operating device connected operatively with the second rock shaft, and a track trip device adapted to engage the said operating devices to actuate one of the same upon movement of the train 85 in one direction and to actuate the other upon movement in the opposite direction.

2. In a device of the class described, the combination of a train-carried indicating apparatus including a rotatably mounted axle, a name-bearing element connected with the axle, a ratchet wheel mounted fixedly upon the axle, a rock shaft journaled parallel to the said axle, a lateral arm provided upon said rock shaft, a dog mounted upon 90 said arm and having a laterally yieldable free extremity normally engaged with the teeth of the said ratchet wheel for operating the latter in one direction upon movement of the rock shaft, a second ratchet wheel connected fixedly with the axle, a second rock shaft journaled parallel to the said axle, a radial arm provided upon the last-named rock shaft, a second dog attached to 95 the said arm and having a radially yieldable free extremity for engagement with the second ratchet wheel to cause movement of the axle in a direction opposite to that in which it is moved by the first-named dog, 100 means for moving each dog outwardly into inoperative position upon operative movement of the other dog, an operating device connected with the first rock shaft and adapted to oscillate the same upon being 105 actuated, and a second operating device connected operatively with the second rock shaft, and a track trip device adapted to engage the said operating devices to actuate one of the same upon movement of the train 110 in one direction and to actuate the other upon movement in the opposite direction, 115 the means for rendering each dog inoperative being in the form of a pivotally mounted tripping arm having one end engaged with one of the said dogs, and an arm pro- 120

vided upon the rock shaft bearing the other dog and connected operatively with the corresponding tripping arm.

3. In a device of the class described, the combination of a train-carried indicating apparatus including a rotatably mounted axle, a name-bearing element connected with the axle, a ratchet wheel mounted fixedly upon the axle, a rock shaft journaled parallel to the said axle, a lateral arm provided upon said rock shaft, a dog mounted upon said arm and having a laterally yieldable free extremity normally engaged with the teeth of the said ratchet wheel for operating the latter in one direction upon movement of the rock shaft, a second ratchet wheel connected fixedly with the axle, a second rock shaft journaled parallel to the said axle, a radial arm provided upon the last-named rock shaft, a second dog attached to the said arm and having a radially yieldable free extremity for engagement with the second ratchet wheel to cause movement of

the axle in a direction opposite to that in which it is moved by the first-named dog, 25 means for moving each dog outwardly into inoperative position upon operative movement of the other dog, an operating device connected with the first rock shaft and adapted to oscillate the same upon being 30 actuated, a second operating device connected operatively with the second rock shaft, and a locking pawl mounted outwardly of each dog and having a yieldable free extremity normally engaging the corresponding ratchet wheel, each locking pawl being adapted to be engaged by the corresponding dog during its movement into inoperative position to be rendered inoperative thereby.

In testimony whereof I affix my signature 40 in presence of two witnesses.

HENRY W. LEWIS.
